W. A. SMITH.

PIN PULLER.

APPLICATION FILED SEPT. 27, 1916.

1,264,216.

Patented Apr. 30, 1918.

Inventor,

William A. Smith.

By

R. J. Winter

Attorney

UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

PIN-PULLER.

1,264,216.

Specification of Letters Patent. Patented Apr. 30, 1918.

Application filed September 27, 1916. Serial No. 122,527.

To all whom it may concern:

Be it known that I, WILLIAM A. SMITH, a citizen of the United States, residing at Denver, in the county of Denver and State 5 of Colorado, have invented certain new and useful Improvements in Pin-Pullers, of which the following is a specification.

As is well known to those skilled in the art, in the production, repair and sharpening of drill bits having openings therethrough, it is the usual custom to temporarily insert a pin in the end of the drill bit being operated on in order to maintain the proper shape of the opening. These pins 10 therefore are apt to become quite tightly wedged in place, and it is the object of the present invention to provide means whereby the pins can be readily extracted from the drill bits after the same are completed. 15 Preferably the device is in the form of an attachment or adjunct to the drill sharpening machine, but is not necessarily so.

An embodiment of the invention is illustrated in the accompanying drawings, 20 wherein:

Figure 1 is a front elevation of a portion of the base of a sharpening machine showing the pin puller thereon.

Fig. 2 is a side elevation of the same, and 25 Fig. 3 is a detail sectional view substantially on the line 3-3 of Fig. 2.

Fig. 4 is a detail view showing a portion of a drill bit and a pin therein to be pulled.

Similar reference numerals designate cor- 30 responding parts in all the figures of the drawings.

In the embodiment illustrated the base only of the drill sharpener is shown and is designated 4. Secured to the upper portion 35 thereof is a horizontal supporting plate or bed 5 having at its front end an upstanding abutment 6. This abutment has in its front side a recess or socket 7 arranged to receive the end of the drill bit, and from the socket 40 an opening or slot 8 is formed through the abutment. This opening is of sufficient size to permit the passage therethrough of the pin to be extracted, but to prevent the passage of the drill bit.

Slidably mounted on the support 5 is a 45 jaw bar 9 that is movable toward and from the rear side of the abutment, the bar having a reduced stem 10 slidably in an eye 11 carried by the rear end of the bed. A coiled 50 spring 12, surrounding the stem and bearing

against the bar and eye, serves to urge said bar toward the abutment. The front end of the bar is provided on its upper face with teeth 13. Another jaw 14 is located over the teeth 13, and is provided on its 60 under face with coacting teeth 15. This jaw is provided with spaced depending legs 16 that straddle the bar 9 and the support 5, so that they act as a guide for the front end of said bar 9. These legs are pivoted to the bar 65 9 as shown at 17.

Suitably fulcrumed on the lower portion of the base 4, as shown at 18, is a treadle 19, and this treadle has a link connection 20 with one end of a bell crank 21 pivoted, as 70 shown at 22, upon the upper portion of the base 4. A link 23 connects the other arm of the bell crank with the legs 16 of the jaw 14. The link 20 passes through a guide eye 24 secured to the base 4 and said eye consti- 75 tutes an abutment having a coiled spring 25 that bears against an abutment collar 26 fixed to the rod 20.

It is understood that in using the afore- 80 said pins in the ends of drill bits, they project beyond the same, and it will thus be evident that when it is desired to remove these pins, all that is necessary is to place the end of the drill bit in the socket 7 with the end of the pin projecting through the slot 8 and 85 between the jaws 9 and 14. The operator thereupon presses downwardly upon the treadle 19 and the first resultant action is the swinging of the jaw 14 down toward the jaw 9 until the end of the pin is firmly 90 grasped therebetween. A further movement of the treadle causes the two jaws to be bodily moved rearwardly against the action of the spring 12, and the pin moving with it, is withdrawn. If the complete rear- 95 ward movement of the jaws is insufficient to completely detach the pin, all that is necessary is to allow the treadle to be elevated, whereupon the jaws will slide forwardly and upon a second depression of the treadle, the 100 pin will be grasped at a new point and further withdrawn.

From the foregoing, it is thought that the construction, operation and many advantages of the herein described invention will 105 be apparent to those skilled in the art, without further description, and it will be understood that within the scope of the claims various changes in the size, shape, proportion and minor details of construction may 110

be resorted to without departing from the spirit or sacrificing any of the advantages of the invention.

Having thus fully described my invention, 5 what I claim as new, and desire to secure by Letters Patent, is:—

1. In apparatus of the character set forth, the combination with a holding device for the drill, of coacting pin grasping jaws movable toward and from the same, operating means for relatively moving the jaws toward each other to grasp a pin and moving said jaws away from the abutment to extract the pin from the drill, and means for automatically releasing the jaws from the pin and returning them toward the abutment when said operating means is released.
2. The combination with a holding device for the drill, of coacting pin grasping jaws 20 movable toward and from the same, operating means connected to one of the jaws for relatively moving the jaws toward each other to grasp a pin and moving said jaws away from the abutment to extract the pin from the drill, and means engaged with the other jaw for automatically returning said jaws toward the abutment when said operating means is released.
3. In apparatus of the character set forth, 30 the combination of a holding device for the drill, of a pin engaging jaw slidable toward and from said device, a spring operating against the jaw to slide it toward the holding device, a jaw pivoted to the first jaw and coacting therewith to grasp a pin introduced between the jaws, and means for swinging the pivoted jaw toward the sliding jaw and causing the movement of the jaws away from the holding device against the action 40 of the spring, said means when released permitting the automatic opening of the jaws and their return toward the abutment by said spring.
4. In apparatus of the character set forth, 45 the combination with a supporting bar having an off-set abutment, of a jaw bar slidable on the supporting bar, a spring bearing against the jaw bar to urge it toward the abutment, a jaw coacting with the jaw bar 50 and pivoted thereto, said jaw having legs straddling both bars, operating means con-

nected to the legs for swinging the jaw and causing its movement with the jaw bar away from the abutment, and means engaged with the operating means for automatically opening the jaw and jaw bar and permitting the return of the same toward the abutment when the operating means is released.

5. In apparatus of the character set forth, the combination with a support, of coacting 60 relatively movable pin grasping jaws that are together movable when engaged with a pin, a treadle, a connection between the treadle and one of the jaws for moving one of the same relatively and also for moving 65 the jaws bodily together, and yielding means opposing the movements of the jaws.

6. In apparatus of the character set forth, the combination with a support, of coacting 70 relatively movable pin grasping jaws that are together movable when engaged with a pin, means for thus moving the jaws, a spring opposing the movement of the jaws, and a spring opposing the movement of the means.

7. In apparatus of the character set forth, the combination with a support having an abutment, of a jaw slidable on the support toward and from the abutment, a spring for urging the jaw toward the abutment, another and coacting jaw pivoted upon the first jaw, and means connected to the last mentioned jaw for swinging the same and causing the bodily movement of both jaws 80 against the action of said spring.

8. In apparatus of the character set forth, the combination with a support having an offset abutment, of a jaw slidable on the support toward and from the abutment, a spring bearing against the jaw for urging it 90 toward the abutment, another jaw pivoted to the first jaw and coacting therewith, a treadle, connections between the treadle and the pivoted jaw, and a spring for causing the pivoted jaw to normally maintain an 95 open position.

In testimony whereof, I affix my signature in the presence of two witnesses.

WILLIAM A. SMITH.
